RAILWAY TRAFFIC CONTROLLING APPARATUS

Ronald A. McCann, Swissvale, and Henry S. Young, Wilkinsburg, Pa., assignors to The Union Switch & Signal Company, Swissvale, Pa., a corporation of Pennsylvania

Application July 8, 1936, Serial No. 89,602

23 Claims. (Cl. 246—134)

Our invention relates to railway traffic controlling apparatus, and more particularly to apparatus for governing the movement of traffic through a track layout including a plurality of track switches which may be arranged to form different traffic routes.

One object of our invention is the provision of means for electrically interlocking the switches and signals in such a manner that the operations of setting up the different traffic routes may be controlled electrically by momentary current impulses produced either by the operation of push buttons or levers or by the transmission of code signals from a remote point. Our apparatus is particularly adapted for use in a centralized traffic control system, and is an improvement upon that disclosed in a pending application for Multiple control apparatus, Serial No. 379,163, filed July 18, 1929, by Charles A. Brooks. A further object of our invention is the provision of a system of route control whereby a plurality of switches may be arranged to set up a route and a signal governing traffic over the route may be cleared in one operation.

In practice, it is usually the case that a large majority of the trains which pass through a track layout such as is herein disclosed are main line trains, and that switching operations are relatively infrequent. In more complicated layouts this situation is emphasized because the number of possible routes is greatly increased, and the use of a majority of these may be extremely infrequent. If this is the case, there is little to be gained, from the standpoint of facilitating operation, in providing route control for such infrequently used routes, while on the other hand, the manipulation of the apparatus may be simplified by the provision of route control for those routes which are the most used, and for which it possesses important advantages in facilitating traffic and in minimizing the number of operations and delay in setting up routes and clearing signals for approaching trains. Furthermore, in any case the provision of facilities for the individual control of the switches may be desired for the reason that it enables trouble with an individual switch of a route to be quickly located. A feature of the present invention resides in an arrangement of apparatus such that both route and function control as above described may be employed in the same plant so as to simplify both the apparatus and its manipulation to the maximum extent.

We will describe three forms of apparatus em-

bodying our invention, and will then point out the novel features thereof in claims.

Referring to the accompanying drawings, Figs. 1A, 1B, and 1C illustrate one form of our apparatus, in which Fig. 1A illustrates the control panel situated at the point of control and includes a miniature representation of the track layout to be controlled together with the control push buttons and suitable indication devices. Fig. 1B shows the switch and signal and route control relays controlled directly by the push buttons of Fig. 1A, while Fig. 1C shows the track layout and the interlocked circuits for controlling the switches and signals thereof in response to the operation of the control relays of Fig. 1B. Fig. 2 shows the control relays of Fig. 1B arranged for control by code signals. This view, when taken with Fig. 1C, illustrates the second form of our apparatus in which the switches and signals are governed by the operation of code signaling apparatus. Fig. 3 shows a modification of a portion of Fig. 2 whereby the control relays are actuated directly by push buttons as in the first form of the apparatus, but in accordance with the positions of interposed switch and signal levers.

Similar reference characters refer to similar parts in each of the several views.

Referring to Fig. 1C, the track diagram shown therein represents the track rails of each of the two main tracks of a double track railway connected by a crossover comprising the switches 3 and 3A, the lower track being also connected to a siding by a single switch 1. While a specific track layout is disclosed, it is to be understood that the apparatus of our invention is adapted to control other track layouts that may involve entirely different combinations of switches and signals, a layout including but one crossover and but one single switch having been chosen to illustrate the principles of our invention for simplicity. An indicated in the drawings, the tracks are divided into sections by insulated joints, and the detector track sections including the track switches are identified by the references 1T and 3T, respectively, while the adjoining approach track sections are indicated by the references 2T, A2T, 4T, and A4T, respectively. Each track section is provided with the usual closed track circuit including a battery 5 and a normally energized track relay in accordance with standard practice, and each track relay is identified by the reference letter TR with a numerical prefix designating the track section to which it corresponds. The track relays 1TR and 3TR each have a slow pickup slow release repeating relay TP associated there-

with, as shown. The movement of traffic over the switches is governed by the signals bearing the references 2 and 4, with distinguishing prefixes R and L indicating the direction of traffic governed by the signals.

In order to simplify the drawings and to enable the circuits to be more readily traced, we have identified each relay contact by a number and each relay by a letter with distinguishing prefix 10 or suffix including a number identifying the switch or signal with which the relay is associated, those contacts not adjacent the respective relays which operate them bearing the reference characters for the respective relays as well as numbers identifying the contacts. Furthermore, instead of showing the sources of current for energizing the relays and the wires leading thereto in detail, we have shown only the terminals of the sources, which we have designated by the reference characters B and N referring to the positive and negative supply terminals, respectively, and by the reference character C, referring to the return or common terminals. Thus, referring to Fig. 1C, the circuit for relay 1TP, for example, may be traced from one terminal B of a source of current, front contact 6 of track relay 1TR, relay 1TP, to the other terminal C of the same source, this circuit being opened when relay 1TR is shunted due to the occupancy of section 1T by a train.

Referring now to Fig. 1A, it will be seen that the track diagram comprises a miniature representation of the track layout of Fig. 1C, and that it includes the usual track indication lamps each of which bears the reference character E with a prefix identifying the track section to which it corresponds. The push buttons for controlling the switches and signals individually are arranged in groups in a row below the diagram. Each group of control buttons takes the place of the usual control lever such as is illustrated for example in the left-hand portion of Fig. 2, and it is to be understood that the operation of each control button corresponds in function to the movement of a control lever to a corresponding position. Directly above the control buttons are corresponding groups of indication lamps, which may be controlled in a well-known manner so as to indicate to the operator the condition of the switches and signals of Fig. 1C. As herein disclosed, the apparatus is so arranged that the main line signals RA2 and LA4 cannot be cleared by the operation of the signal control buttons located below the diagram, the clearing of these signals being effected by the operation of special route control buttons R2P and L4P, respectively, which are located in the track diagram at the entrance to the main line routes b—e and d—a, which these signals govern. A single operation of a route button serves to operate the track switches to set up the corresponding main line route and to then clear the signal R2A or L4A to permit a train to pass over the route, provided conditions are proper so that the switches are free to be operated as indicated by the lighting of the route lamp R2E or L4E adjacent the route button. Each route button also has associated with it a "call-on" button 2U or 4U, which may be operated to admit a train at slow speed to a route already occupied by a preceding train, in accordance with the usual practice.

Fig. 1B illustrates the circuits which are controlled directly by the push buttons of Fig. 1A and includes normal and reverse switch stick relays NWS and RWS controlled by the switch con-

trol buttons N and R, signal stick relays LHS and RHS controlled by the signal control buttons L and R for clearing the signals, call-on stick relays US controlled by the call-on buttons U, and route stick relays RS controlled by the route buttons P. In addition, a normal signal control button N is provided for each group of signals for releasing the relays HS, RS, and US to put the cleared signal to stop. The circuits for the stick relays of Fig. 1B are also governed by the apparatus of Fig. 1C, and further consideration of these circuits will therefore be deferred until after this apparatus has been explained in detail.

Referring to Fig. 1C, the single switch 1 is actuated by a power-operated switch machine 1SM of any suitable type, such, for example as the one disclosed in the Zabel Patents Nos. 1,293,290 and 1,413,820, and the crossover switches 3 and 3A are actuated by similar switch machines 3SM and 3ASM. Each switch machine SM is provided with the usual motor having its operating circuits controlled by the contacts of a polarized switch control relay WR in the manner disclosed in the Willard Patent No. 1,380,452, as indicated diagrammatically by dotted line connections in the drawings, so that the switch or switches will be operated to normal or reverse, when the control relay WR is energized and its polar contacts are closed to the left or right, respectively. Each relay WR is controlled by the manually governed switch stick relays NWS and RWS of Fig. 1B and by a switch locking relay MP. The locking relays MP are controlled in turn by the track relays TR and their repeaters TP for the respective switch sections, and by approach locking relays LMR and RMR which are controlled by the signals. Relay 1WR is also controlled by a section locking relay 1WS.

Each switch machine is provided with the usual circuit controller, as disclosed in the Zabel patents hereinbefore referred to, for controlling a polarized indication relay KR, as indicated diagrammatically by dotted line connections in the drawings. For an understanding of the present invention it will suffice to point out that when switch machines 3SM and 3ASM are locked normal or reverse, relay 3KR will be energized with its polar contacts closed to the left or right, respectively, and that relay 1KR is similarly controlled by switch machine 1SM. Each relay KR is provided with a pair of repeating relays NKP and RKP each of which is energized only when the polarized relay KR is energized in a position corresponding to that of the associated switch control relay WR. Thus the circuit for the normal repeater 1NKP for switch 1 may be traced from terminal B, neutral contact 14 and left-hand polar contact 15 of relay 1KR, relay 1NKP, left-hand polar contact 16 and neutral contact 17 of relay 1WR to terminal C. The circuits for the reverse switch repeater 1RKP and for the corresponding relays 3NKP and 3RKP for the crossover are similar and may be readily traced from the drawings.

The circuit for the locking relay 2MP may be traced from terminal B, front contacts 18 and 19 of the approach locking relays R2MR and L2MR controlled by signals 2, contacts 20 and 21 of relays 1TP and 1TR, contact 22 of relay 1WS, relay 2MP to terminal C, while the circuit for relay 4MP may be traced from terminal B, contacts 18, 19, 20, and 21, front contacts 23 and 24 of track relay 3TR and its repeater 3TP, front contacts 25 and 26 of the approach locking relays L4MR 75

and R4MR controlled by signals 4, relay 4MP to terminal C. The section locking relay 1WS has a pickup circuit which may be traced from terminal B, front contacts 27 and 28 of relays 3NKR and 3TR, relay 1WS to terminal C and a stick circuit including contact 30 and its own front contact 29. As hereinafter explained, each approach locking relay such as relay L4MR is controlled by the associated signals in such a manner that it will become released when the signal, in this case, signal LA4 or LB4, is cleared. Relay L4MR has a front contact 30 bridging contact 27 in the circuits for relay 1WS, and it follows that if the route $d-b$ or $d-c$ has been set up, contact 27 will be open and if signal LB4 is cleared, contact 30 will open to release relay 1WS to open contact 22 in the circuit for relay 2MP, so as to lock switch 1, but switch 1 is not locked if route $d-a$ is set up and signal LA4 is cleared because in this case contact 27 will be closed.

The switch control relay 1WR has a normal control circuit which may be traced from terminal B, front contact 31 and back contact 32 of the switch control relays 1NWS and 1RWS, front contact 33 of relay 2MP, relay 1WR to terminal C, and a reverse control circuit which extends from terminal N over back contact 34 and front contact 32 of relays 1NWS and 1RWS, contact 33, relay 1WR to terminal C, so that relay 1WR may be operated to normal by energizing relay 1NWS, or to reverse by energizing relay 1RWS, provided relay 2MP is energized. It will be apparent from the foregoing that relay 2MP can be energized only when conditions are favorable for operating switch 1, namely, when signals 2 are at stop and section 1T is unoccupied, and that if the crossover is reversed signal LB4 which then governs movements in one direction over switch 1 must also be at stop.

When the switch completes its movement in response to an operation of relay 1WR, relay 1KR will become energized in a corresponding direction, and if a signal is then cleared to release relay 2MP and to thereby lock switch 1, relay 1WR will remain energized due to the closing of a holding circuit which may be traced from terminal B or N as the case may be, contacts 35 and 36 of relay 1KR, back contact 33 of relay 2MP, relay 1WR to terminal C, thereby holding the switch in its last-operated position as long as relay 2MP is deenergized.

The crossover control relay 3WR is similarly controlled by the switch control relays 3NWS and 3RWS and by the locking relay 4MP, and it will be apparent from the drawings that relay 4MP will be energized to permit operation of switches 3 and 3A only when all the signals 2 and 4 are at stop and sections 1T and 3T are both unoccupied.

The signals shown in Fig. 1C may be of any suitable type and in practice those signals governing high speed routes will generally be three-position signals governed in accordance with the condition of other signals in advance, not shown herein, in addition to being subject to manual and track circuit control. To illustrate the present invention, however, it is deemed sufficient to assume merely that each signal indicates proceed when energized and indicates stop when deenergized. A signal relay H is provided for each signal arm, and each signal relay H controls one or more circuits for the signal as indicated diagrammatically by dotted line connections from the contacts of the relays H to the signals of the track diagram.

The circuits for the approach locking relays LMR and RMR will in practice generally include time or approach locking features which not being part of the present invention have been omitted to simplify the drawings, and these relays may be arranged for example, as disclosed in Patent No. 2,046,049, for Railway traffic controlling apparatus, granted June 30, 1936, to Earl M. Allen. To illustrate the present invention, it is deemed sufficient to point out that each relay MR is energized only when the signals which control it are at stop. Thus, in the lower portion of Fig. 1C, a circuit for relay R2MR is indicated as extending from terminal B over back contacts 37, 38, and 39 of the signal relays RA2H, RB2H, and RC2H for the three signals R2, through relay R2MR to terminal C, a portion of this circuit being shown dotted to indicate the omission of the approach or time control. The circuits of the remaining approach locking relays MR are generally similar and will be readily understood from the drawings. A transverse arrow has been added to each of the front contacts of the MR relays to indicate that these contacts are slow to close, but it is to be understood that in accordance with usual practice the delay in the energization of these relays is nullified when a signal is put to stop automatically by a train and also when it is put to stop manually and the approach section is unoccupied.

The signal relays H are controlled over the signal relay network shown in the lower portion of Fig. 1C, the circuit for each signal relay H being controlled by front contacts of a signal control relay HS or a route relay RS for the corresponding signal or route and by a back contact of a signal control relay HS or route relay RS for an opposing signal. Disregarding the branch circuits controlled by the call-on stick relays US, it will be seen that signal relay network is a counterpart of the track layout and includes a circuit for each direction for each route through the layout, each circuit being formed by conductors corresponding to portions of the track which are connected together by indication relay contacts controlled in accordance with the positions of the track switches. The route circuit for each signal is connected to terminal B of the source of current over a front contact of the approach locking relay MR associated with the opposing signal, thereby not only insuring that a signal cannot be cleared unless the opposing signal indicates stop, but also interposing a time delay in the reversal of the direction of traffic when this feature is embodied in the circuits for the relays MR.

Assuming that switches 1, 3, and 3A are normal and sections 1T and 3T unoccupied, if relay R2RS is picked up and relay L2HS is released, relay RA2H will be energized over a circuit from terminal B, contact 40 of relay L2MR, back contact 41 of relay L2HS, front contacts 42, 43, and 44 of relays 3NKP, 1KR, and R2RS, back contact 45 of relay 2US, front contacts 46 and 47 of relays 3NKP and 1NKP, front contacts 48 and 49 of the track relays 1TR and 2TR, relay RA2H, back contact 50 of relay 1RKP, and front contact 51 of relay R2RS to terminal C. It follows that the high speed signal RA2 will be cleared for a train movement from left to right over the lower main track in response to the energization of the route relay R2RS when the route $b-e$ is set up provided signal L2 is at stop and sections 1T and 2T are unoccupied. Similarly, the corresponding relay LA4H will be energized to clear

- signal **LA4** for a train movement from right to left over the upper main track in response to the energization of the route relay **L4RS** when the route **d—a** is set up, provided signal **R4** is at stop and sections **3T** and **4T** unoccupied. This will be apparent from the drawings, since the circuit for relay **LA4H** is similar to that just traced except that it is not controlled by switch **1**.
- 10 If now the call-on stick relay **2US** is energized, relay **RA2H** will be deenergized and a branch of its control circuit will be completed over front contacts **52** and **53** of relays **3NKP** and **1NKP**, through relay **RB2H** and back contact **54** of relay **RA2H**. It is evident, therefore, that after relay **R2RS** has been energized and route **b—e** has been set up, relay **RB2H** may be energized to clear the slow speed signal **RB2** to permit a train to enter route **b—e**, even though section **1T** or **2T** is occupied and contact **48** or **49** is open. The call-on stick relay **4US** may likewise be operated to energize relay **LB4H** for clearing signal **LB4** under corresponding conditions to permit a slow speed movement over route **d—a**.
- 25 Assuming switch **1** reversed and switches **3** and **3A** normal, if relay **R2HS** is energized, a circuit may be closed from terminal **B**, front contact **40** of relay **L2MR**, back contact **41** of relay **L2HS**, front contacts **42** and **43** of relays **3NKP** and **1NKP**, back contact **44** of relay **R2RS**, front contacts **56** and **64** of relays **R2HS** and **1RKP**, relay **RC2H**, front contacts **50** and **63** of relays **1RKP** and **R2HS** to terminal **C**. Relay **RC2H** may therefore be energized in response to the energization of relay **R2HS** to clear signal **RC2**, provided route **c—e** is set up and signal **L2** is at stop.
- 30 Assuming switches **3** and **3A** normal, if relay **L2HS** is energized, a circuit may be closed from terminal **B**, front contact **55** of relay **R2MR**, back contacts **56** and **44** of relays **R2HS** and **R2RS**, front contacts **43**, **42**, and **41** of relays **1KR**, **3NKP**, and **L2HS**, relay **L2H**, front contact **57** of relay **L2HS** to terminal **C**. Relay **L2H** may therefore be energized in response to the energization of relay **L2HS** to clear signal **L2**, provided either route **e—b** or **e—c** is set up and signals **RA2**, **RB2**, and **RC2** are at stop. Similarly, relay **R4H** may be energized in response to the energization of relay **R4HS** to clear signal **R4** under corresponding conditions to permit a slow speed movement over route **a—d**, as will be apparent from the drawings.
- 35 Assuming that switch **1** is normal and switches **3** and **3A** are reversed and that relays **R2HS** is energized, a circuit will be closed from terminal **B**, front contact **58** of relay **L4MR**, back contacts **59** and **60** of relays **L4HS** and **L4RS**, front contacts **61** and **63** of relays **3RKP** and **1KR**, back contact **44** of relay **R2RS**, front contacts **56**, **62**, **60** and **53** of relays **R2HS**, **3RKP**, and **1NKP**, relay **RB2H**, back contacts **54** and **50** of relays **RA2H** and **1RKP**, front contact **63** of relay **R2HS** to terminal **C**, so that relay **RB2H** will be energized to clear signal **RB2** in response to the energization of relay **R2HS** when route **b—d** is set up and signals **LA4** and **LB4** are at stop. If switch **1** is reversed, contact **53** in the circuit just traced will be open and this contact and relay **RB2H** will be shunted by a branch including front contacts **64** and **50** of relay **1RKP** and the winding of relay **RC2H**. It follows therefore that relay **RC2H** will be energized to clear signal **RC2** in response to the energization of relay **R2HS** when route **c—d** is set up and signals **LA4** and **LB4** are at stop. The circuit for the corresponding opposing

signal relay **LB4H** includes front contact **43** of relay **IKR** which is closed in both the normal and reverse positions of switch **1** but is otherwise similar to the circuit just traced and it is evident that relay **L4BH** will be energized to clear signal **L4B** in response to the energization of relay **L4HS** when either route **d—b** or **d—c** is set up, provided the signals **R2** are at stop.

Having now explained in detail how the apparatus of Fig. 1C is controlled by the stick relays of Fig. 1B, we will next point out how these relays are controlled.

Referring to Fig. 1B, and assuming that relay **R2RS** is deenergized and that conditions are proper for operating switch **1** so that relay **2MP** is energized as already described, it is apparent that relay **1NWS** may be energized by the momentary operation of push button **1N** and that relay **1RWS** may be energized by the momentary operation of push button **1R**, and that each of these relays when energized releases the other to complete its own stick circuit. Thus for example, the operation of push button **1R** completes a circuit from terminal **B**, contacts **66** and **65**, relay **1RWS** to terminal **C**, whereupon relay **1RWS** picks up, opening contact **67** to release relay **1NWS** to complete the stick circuit for relay **1RWS** over contacts **68** and **69**. It is also apparent that relays **3NWS** and **3RWS** are similarly controlled by push buttons **3N** and **3R**.

The circuits for the signal stick relays **LHS** and **RHS** are arranged to prevent their energization unless the approach locking relays associated with conflicting or opposing signals are energized, and also when the routes governed by the stick relays are not available. The signal stick relays and also the route relays **RS** are released manually only by the operation of a signal stop key **N**, so that when a signal has been cleared it cannot be put to stop or otherwise interfered with by the operation of any push button **L** or **R** governing another signal. Thus, for example, relay **L2HS** has a pickup circuit extending from terminal **B** over push button **2L**, front contacts **71** and **72** of relays **R2MR** and **3NWS**, relay **L2HS**, back contacts **73** and **70** of relays **R2HS** and **R2RS**, push button **2N** to terminal **C**, and when relay **L2HS** becomes energized it opens contacts **74** and **75** in the circuits for relays **R2HS** and **R2RS**, respectively.

The pickup circuit for the signal stick relay **L4HS** is arranged somewhat differently. When the crossover is normal, its pickup circuit includes contacts **84** and **93** of relays **3NKP** and **R4MR** and can be closed only when signal **R4** is at stop, but if the crossover is reversed, contact **84** will be opened and the circuit will then include contact **83** of relay **R2MR** so that it can be closed only when the opposing signals **R2** are at stop. The circuits for relays **R4HS** and **R2HS** are similar to those for relays **L2HS** and **L4HS**, respectively, as is apparent from the drawings.

The route stick relays **RS** not only control the signals, as already explained, but also govern the switch stick relays controlling the switches for their respective routes. For example, relay **R2RS** controls front contacts **76** and **77** in the circuits for relays **1NWS** and **3NWS** and back contacts **66** and **78** in the circuits **1RWS** and **3RWS**. The switches **1**, **3**, and **3A** are therefore operated to normal by the energization of relay **R2RS** and are held normal as long as relay **R2RS** is energized, the switch control buttons being rendered temporarily inoperative. Relay **75**

R2RS, shown in Fig. 1B, is energized over a circuit which may be traced from terminal B, front contacts 79 and 80 of relays 1NKP and 3NKP, back contact 75 of relay L2HS, push button R2P, 5 relay R2RS, push button 2N to terminal C. Contacts 79 and 80 are bridged by contacts 81 and 82 of the switch locking relays 2MP and 4MP, respectively, and it is evident, therefore, that relay R2RS may become energized only when the 10 switches are normal or the condition of the switch locking is such that they may be operated to normal. This condition is made manifest by the energization of the route indication lamp R2E over a branch of the circuit just traced, as will be clear from the drawings. Relay R2RS is released not only by the operation of key 2N, but 15 is also released when a train enters section 1T by the momentary opening of its stick circuit at contacts 86 and 87 as relays 1TR and 1TP release 20 successively, in a well-known manner. The circuit for the route stick relay L4RS is similar to that for relay R2RS, except that it is independent of the condition of switch 1, as is apparent from the drawings.

25 The call-on stick relays US are stick repeaters of the route relays RS and are controlled by their respective push buttons U in a manner that will be obvious from the drawings. The remaining relays of Fig. 1B are similar in function to one 30 or another of those which have been described, and it is thought that a detailed tracing of their circuits is unnecessary and that their operation will be readily understood from the description of the operation of the apparatus which follows.

35 In describing the operation of the first form of the apparatus as illustrated in Figs. 1A, 1B, and 1C, it will first be assumed that the apparatus is in the condition shown in the drawings and that a train movement over route c-d is to be effected. The operator will first actuate push buttons 1R and 3R, thereby energizing relays 1RWS and 3RWS and releasing relays 1NWS and 3NWS, whereupon relays 1WR and 3WR will become energized in the reverse direction to release relays 1NKP and 3NKP and to operate the 40 switch machines 1SM, 3SM, and 3ASM to reverse. The operator will then actuate push button 2R to energize relay R2HS, without necessarily waiting until the switches complete their movement, thereby closing contacts 56 and 63 in the circuit for the signal relay RC2H. When switch 1 completes its movement and becomes locked reverse, relays 1KR and 1RKP become energized to close contacts 43, 64, and 50 in the circuit for relay RC2H, and when switches 3 and 3A both complete their movements and become locked reverse, contact 61 closes to complete the circuit for relay RC2H. Relay RC2H then becomes energized, clearing signal RC2. Relay 45 R2MR releases due to the opening of contact 39 and in turn by opening contact 18 releases relays 2MP and 4MP, and the latter relays open the circuits controlled by each of the push buttons 1N, 1R, 3N, 3R, R2P, and L4P so that the inadvertent operation of any of these push buttons will be 50 without effect as long as the signal is at clear. Push button 2L is now ineffective because the circuit it controls is open at contacts 71, 72, and 73; push button 4L is ineffective because the circuit it controls is open at the multiple contacts 83 and 84; and push button 4R is ineffective because the circuit it controls is open at contact 85 of relay 3NWS. It is evident, therefore, that the route which has been set up is effectively 55 locked by the clearing of the signal, so that the

signal cannot be interfered with except in a proper manner, namely, by the operation of the release push button 2N. When the train accepts the signal, the operator will actuate button 2N, releasing relays R2HS and RC2H to put signal 5 RC2 to stop, thereby reenergizing relay R2MR. When the train vacates section 1T, relay 2MP will become energized and when it vacates section 3T, relay 4MP will become energized to release the switch locking.

10 It will now be assumed that the next train movement to be effected is over route b-e. After lamp R2E becomes lighted to indicate the release of the switch locking, the operator will actuate the route button R2P, thereby energizing relay 15 R2RS over the branch circuit including contacts 81 and 82, and this relay by closing contacts 76 and 77 will effect the energization of relays 1NWS and 3NWS and the release of relays 1RWS and 3RWS. Relays 1WR and 3WR will then become 20 energized in the normal direction, releasing relays 1RWP and 3RWP and operating the switches to normal. Front contacts 44 and 51 of relay R2RS in the signal network are now closed, and relay RA2H will become energized to clear signal RA2 25 as soon as the switches complete their movement and the normal indication relays become energized, and then relay R2MR will release due to the opening of contact 37, and relays 2MP and 4MP will release, the switch control buttons being rendered ineffective both by the opening of the front contacts of these relays and by the opening of the front contacts of relay R2RS included in the circuits for the switch control relays. Buttons 4L, 4R, and L4P remain effective 30 to control their respective stick relays, but since switch 3A is locked normal the routes which these buttons govern do not conflict with route b-e. The route button R2P remains effective 35 to control relay R2RS because it now has a connection to terminal B over contacts 79 and 80.

40 It will next be assumed that the train enters route b-e and that the call-on signal RB2 is to be cleared to permit a following train to enter the same route. When the first train enters 45 section 1T, the opening of contacts 6, 48, and 86 of relay 1TR causes relays 1TP, RA2H, and R2RS to become deenergized. Relay 1TP being slow acting will release after relay R2RS has released. The operator will now actuate button 50 R2P to pick up relay R2RS again, and this relay will be held energized over back contact 87 of relay 1TP, but relay RA2H will remain deenergized, contact 48 of relay 1TR and presumably also contact 49 of relay 2TR being open. The operator will also actuate button 2U to pick up relay 2US over contact 88 of relay R2RS, thereby closing front contact 45 in the signal network to complete the circuit for relay RB2H to clear signal RB2.

55 When the second train passes signal RB2, the route set up will be released automatically in case the first train has already vacated section 1T, but in case the second train enters section 1T before the first train leaves that section, the 60 relays R2RS and 2US may be released manually by the operation of the release button 2N.

65 The operations of setting up two of the five possible routes from left to right through the layout have now been traced in detail, and it is believed that the operations of setting up the remaining routes will be readily understood without further explanation. Certain features of the locking of these additional routes, however, will now be pointed out.

Considering route *b-d*, for example, when signal *R2Z* for this route is cleared relay *R2MR* releases and opens the circuits controlled by push buttons *2L* and *4L*, and by releasing relays *2MP* 5 and *4MP* opens the circuit controlled by the switch and route buttons, and since relay *3NWS* is released, the circuit controlled by push button *4R* is open at contact *85*, so that the locking conditions are the same as for route *c-d* already 10 described in detail. In the case of route *c-e*, when relay *R2MR* releases it opens the circuit controlled by push button *2L*, but the circuits controlled by the push buttons *4L*, *4R*, and *L4P* are not interfered with. In this case, the locking 15 conditions correspond to those for route *b-e*, that is, the clearing of signal *RC2* for a train movement over route *c-e* does not lock the non-conflicting route *a-d*.

In the case of route *a-d*, the energization of 20 *R4HS* opens contacts *89* and *90* to render push buttons *4L* and *L4P* ineffective, and the clearing of signal *R4* releases relays *R4MR* and *4MP* to open contacts *91* and *92* to render push buttons *3N* and *3R* ineffective. It will be evident 25 therefore that the clearing of signal *R4* does not lock the non-conflicting routes *b-e* and *c-e*.

The control circuits for governing train movements in the opposite direction through the track layout are generally similar and will be readily 30 understood from the foregoing description. It will be clear that in more complicated layouts several pairs of signal stick relays may be required, and in such cases at least one stick relay of each pair will be interlocked with the opposing 35 relays of one or more different pairs through the medium of the existing approach locking relays. In any case, in accordance with this feature of our invention, the circuits will be so arranged that all of the switch and signal control 40 buttons or levers of the control panel which if operated conflict with the route set up or the signal that has been cleared are rendered temporarily ineffective without the provision of any special lock-out relays or route networks such as 45 have heretofore been considered necessary in interlocking apparatus of this character.

Another feature of our invention resides in the traffic direction control provided by the approach locking relay contacts in the circuits for 50 the control relays. Thus for example, if signal *R4* is put to stop by releasing *R4HS*, the push button *4L* controlling the opposing slow speed signal *LB4* remains inoperative as long as contact *93* of relay *R4MR* remains open, so that the restoration 55 of the operator's control over button *4L* to reverse the direction of traffic is delayed for the time period involved in the operation of relay *R4MR*. As herein illustrated, this feature is provided for each slow speed signal but is omitted in 60 the case of the high speed signals for the reason that these are provided with track circuit control by the track sections *2T* and *4T* which are in approach to the opposing signal. In accordance 65 with a further feature of our invention the locking of the control relays is extended to include cases in which the operation of the relays could not interfere with the existing route. This feature is illustrated by contacts *72* and *85* of relay *3NWS* in the circuits for relays *L2HS* and *R4HS*. 70 These contacts serve to insure that the manipulation of the control buttons occurs in the proper sequence when signal *L2* or *R4* is to be cleared and also insures that these relays will not be inadvertently energized when the crossover is reversed, in which case they would interfere with 75

the clearing of an opposing signal if allowed to remain energized after the crossover has been restored to normal.

The apparatus of our invention is particularly adapted for remote control by means of a selective 5 communication system of any suitable type, and to illustrate one manner in which the locking of our control relays may be arranged when our apparatus is remotely controlled we have shown in Fig. 2 the stick relays of Fig. 1B so arranged that 10 they may be controlled by the field station apparatus of a code system of centralized traffic control of a well-known type. To understand the relation between the communication system and our apparatus, it is deemed sufficient to merely 15 point out that the field station portion of the system which is at the location of the track layout of Fig. 1C includes a plurality of delivery relays *D*, each of which is selectively and momentarily energized at times in response to a code signal transmitted from a distant control office, while at the same time one or more of a group of selecting relays *9*, *10*, *11*, *12* are also energized by certain elements of the code in accordance with the positions of the control levers of one of a plurality of groups 20 of levers located in the control office and with which the operated relay *D* is identified. To illustrate such control, the energization of the various relays in accordance with the various lever positions is indicated diagrammatically by dotted 25 line connections in the drawings. It is to be understood that actually there is but one set of relays *9* to *12* for the three delivery relays *1D*, *2D*, and *3D*, and that the showing of the relays *9* to *12* is repeated in order to more clearly indicate 30 their control by different groups of levers.

The operation of the second form of the apparatus as shown in Fig. 2 will be explained by assuming that the apparatus of Fig. 1C is in the condition shown in the drawings and that a train 40 movement over route *c-e* is to be effected. The operator will reverse the control lever "Sw. 1" of Fig. 2 and also will move the lever "Sig. 2" to position *R* and will then initiate the transmission of the proper code resulting in the momentary energization of relays *11*, *12*, and *1D*. Contacts *94* and *95* therefore close to energize relay *1RWS*, corresponding to an operation of button *1R* of Fig. 1B, and contact *96* opens to release relay *1NWS*. At the same time contacts *97* and *98* close to energize relay *R2HS*, corresponding to an operation of button *2R* of Fig. 1B, and when relay *1D* releases, its back contacts *96* and *99* close to complete the stick circuits for relays *1RWS* and *R2HS*. Relay *1NWS* and the indication relay *1NKR* are arranged to be quick in releasing so that the signal circuits controlled by relay *R2HS* are immediately opened and the energization of this relay is without effect until switch *1* has completed its movement in response to the energization of relay *1RWS*, the switch and signal operations being similar to those hereinbefore described.

It is to be noted that in Fig. 2 when the route relay *R2RS* is energized, relay *1NWS* is steadily 65 energized and also that when relay *2MP* is released the closing of its back contact *100* maintains relay *1NWS* or *1RWS* energized. It is evident, therefore, that these relays cannot be interfered with if relay *1D* is operated when relay 70 *R2RS* is energized or relay *2MP* is released.

To restore a signal to stop by the apparatus of Fig. 2, a code is transmitted to energize the selected delivery relay such as *1D* with the corresponding signal lever in its mid-position, and in this 75

case relays 12 and 10 are not energized so that the effect of the code is to momentarily open the stick circuits for the signal control relays at contact 99 to release the energized stick relay.

5 The group of apparatus controlled by relay 2D includes the control relays for switches 3 and 3A and signals 4 with locking circuits similar to those of the similar relays of Fig. 1B, and the operation of these relays will be readily understood 10 from the description of the circuits controlled by relay 1D.

While in many cases a route may be set up by sending one code to operate the stick relays controlled by delivery relay 1D only, or to operate those controlled by delivery relay 2D only, the operation of stick relays in both groups may be required if neither switch 1 nor the crossover are in the proper position. Switch 1 and the crossover may be restored to normal either 20 by sending a single code under control of delivery relay 3D to energize relay R2RS, to thereby energize the two stick relays 1NWS and 3NWS simultaneously, or by sending two codes in succession to operate relays 1D and 2D. In the latter case 25 the order in which the two codes are transmitted is made such that the one which includes the signal control element for the signal that is to be cleared is transmitted last.

One advantage of the route control feature of 30 this form of our invention is that a route involving a whole series of switches may be set up and cleared by the transmission of but one code, thereby avoiding any difficulty that might arise due to the failure of the apparatus to fully receive one or more codes of a series.

35 The route relays RS and the associated call-on relays US are shown in Fig. 2 controlled by the usual push buttons through the medium of relays 3D and 9 to 12, and since the circuits are otherwise the same as those already described for 40 these relays, their operation will be readily apparent from the drawings. Thus for example, if push button R2P is closed, the operation of relay 3D will complete a circuit over contacts 101 and 102 to pick up relay R2RS, provided conditions 45 are proper, and relay R2RS will control both the switch 1 and crossover 3 as may be required so as to set up route b—e, as hereinbefore described while if push button R2P is open, the operation 50 of relay 3D will open contact 103 momentarily to effect the manual release of relay R2RS, to cancel route b—e.

55 In illustrating this form of our invention, we have assumed that each switch or crossover and the associated pair of opposing signals will be controlled by the same code and by a single relay D. It is obvious, however, that individual codes may be employed, and that relays 1NWS and 1RWS may, for example, be controlled by one 60 relay D and relays L2HS and R2HS by another relay D. This is because the arrangement of the apparatus of our invention is such that these relays D may be operated at any time whatsoever and the control relays will respond to their 65 manual control only when conditions are favorable for their operation.

Furthermore, the direct wire control and the code control forms of our invention are interchangeable and both may be employed for controlling different portions of the same track layout. In such cases, for the sake of uniformity, and also in certain cases where no code control is to be used, it may be preferable to employ lever control instead of push button control for those 70 control relays which have direct wire connections 75

to the control panel, in the manner illustrated in Fig. 3. It is to be understood that in the third form of our apparatus, Fig. 3 replaces the portion of Fig. 2 at the left of the line x—y, and it will be readily apparent without tracing the circuits in detail that the switch and signal control relays of Fig. 2 may be operated in accordance with the positions of the switch and signal levers of Fig. 3 by the momentary operation of the push buttons 1P or 2P so that these relays will function as in Fig. 1B or 2, and that the operation of the push buttons controlling the route and call-on relays in Fig. 3 is precisely the same as in Fig. 1B.

5 While we have, in the foregoing, illustrated the several forms of the apparatus of our invention by reference to a relatively simple track layout, it will be clear that the same principles can be applied to complicated layouts involving large 10 numbers of traffic routes and that the system of our invention provides relatively simple and reliable apparatus for safely controlling interlocked railway track switches and signals from a 15 remotely located office or cabin, in such a manner that a train cannot be run over a route different from the intended route due to failure of a switch 20 to respond to an operation of its control means and likewise that our system is so arranged as to provide a maximum degree of protection 25 against interference with the movement of traffic when a signal has been cleared for an approaching train.

30 Although we have herein shown and described only three forms of apparatus embodying our invention, it is understood that various changes and modifications may be made therein within the 35 scope of the appended claims without departing from the spirit and scope of our invention.

Having thus described our invention, what we claim is:

1. In combination, a traffic route including a 40 railway track switch, a signal at each end of the route to govern the movement of traffic in opposite directions over the route, a switch locking relay for each signal, manually controllable switch control means effective to control the 45 switch only when said locking relays are energized, a signal control relay for each signal, a manually controllable pickup circuit for each signal control relay closed only when the locking relay for the opposing signal is energized and the 50 signal control relay for the opposing signal is deenergized, a manually controllable stick circuit for each signal control relay, an energizing circuit for each locking relay closed only when the associated signal control relay is deenergized, 55 and a circuit for clearing each signal controlled in accordance with the position of the track switch and closed only when the associated signal control relay is energized and the signal control relay for the opposing signal is deenergized. 60

2. In combination, a traffic route including a railway track switch, a signal at each end of the route to govern the movement of traffic in opposite directions over the switch, manually controllable switch control means for controlling the 65 operation of said switch; a signal relay, a signal control relay and a switch locking relay for each signal; an energizing circuit for each signal relay closed only when the associated signal control relay is energized provided said switch agrees 70 as to position with its control means, the signal control relay for the opposing signal is deenergized, and the switch locking relay for the opposing signal is energized; manually operable means for energizing each signal control relay effective 75

- only when the locking relay associated with the opposing signal is deenergized, means for energizing each switch control relay only when the associated signal relay is deenergized, and means 5 preventing the operation of the track switch in response to the operation of its control means when either of said locking relays is deenergized.
3. In combination, a traffic route including a plurality of railway track switches, two opposing 10 signals including one at each end of the route to govern the movement of traffic in opposite directions over the route, manually controllable switch control means for controlling the operation of each switch of the route; a signal relay, a signal control relay and a switch locking relay for each signal; an energizing circuit for each signal relay closed only when the associated signal control relay is energized and the opposing signal control relay is deenergized provided each 15 switch of the route agrees as to position with its switch control means, an energizing circuit for each locking relay closed only when the associated signal relay is deenergized, a manually controllable circuit for each signal control relay including a front contact of the locking relay for the opposing signal, and switch locking means including front contacts of each of said locking relays for rendering the track switches responsive to the 20 operation of said switch control means.
4. In combination, a traffic route including a railway track switch, a signal at each end of the route to govern the movement of traffic in opposite directions over the route, a switch locking relay associated with each signal, manually 25 controllable switch control means effective to control the switch only when said switch locking relays are energized, a signal control relay for each signal having a manually controllable energizing circuit, a signal circuit for clearing each signal controlled in accordance with the position of the track switch and including front contacts of the associated signal control relay and back contacts of the opposing signal control relay, means responsive to the closing of said signal circuit for deenergizing the associated switch locking relay, and means for preventing the operation of the opposing signal control relay as long as said switch locking relay remains deenergized. 30
5. In combination, a traffic route including a railway track switch, a signal at each end of the route to govern the movement of traffic in opposite directions over the route, a switch locking relay associated with each signal, manually controllable switch control means effective to control the switch only when said locking relays are energized, a signal control relay for each signal having a manually controllable energizing circuit, a signal circuit for clearing each signal controlled in accordance with the position of the track switch and including front contacts of the associated signal control relay and back contacts of the opposing signal control relay, means responsive to the closing of said signal circuit for deenergizing the associated switch locking relay, and means selected in accordance with the position of the track switch for preventing the operation of the opposing signal control relay as long as said switch locking relay remains deenergized. 35
6. In combination with a railway track switch, a plurality of traffic routes over the switch, a signal at each end of each route for governing the movement of traffic in opposite directions over the route, a switch locking relay associated with each signal, manually controllable switch control means effective to control the switch only 40
- when said locking relays are energized, a signal control relay for each signal having a manually controllable energizing circuit, a signal circuit for clearing each signal including front contacts of the associated signal control relay and back contacts of an opposing signal control relay selected in accordance with the position of the track switch, means responsive to the closing of any signal circuit for deenergizing the associated switch locking relay, and means selected in accordance with the position of the track switch for preventing the operation of the opposing signal control relay as long as said switch locking relay remains deenergized. 45
7. In combination, a track layout including a plurality of parallel tracks interconnected by track switches to form different traffic routes, a signal at each end of each route to govern the movement of traffic in opposite directions over the route, a switch locking relay associated with each signal, manually controllable switch control means for each switch, means including said switch locking relays for preventing the operation of each switch when a signal has been cleared to permit a train movement over a route that includes the switch, a manually controllable signal control relay for each end of each route, a signal network comprising a plurality of interconnected signal circuits including one for each route, each of which includes front contacts for the signal control relay for one end of the route, contacts closed in accordance with the positions of the switches of the route, and back contacts of the signal control relay for the opposite end of the route, means responsive to the closing of any signal circuit for deenergizing the associated switch locking relay, and means controlled by said switch locking relay when deenergized for preventing the operation of the signal control relay at the opposite end of the same route. 50
8. In combination, a track layout including a plurality of parallel tracks interconnected by track switches to form different traffic routes, a signal at each end of each route to govern the movement of traffic in opposite directions over the route, a switch locking relay associated with each signal, a manually controllable signal control relay for each end of each route, a signal circuit for clearing each signal closed in response to the energization of the associated signal control relay and including back contacts of an opposing signal control relay, means responsive to the closing of any signal circuit for deenergizing the associated switch locking relay, means responsive to the deenergization of said switch locking relay for preventing the operation of any switch of the established route, and means controlled in part by said switch locking relay when deenergized for preventing the operation of any of said signal control relays for controlling a signal governing an opposing or conflicting route. 55
9. In combination with a railway track switch, a plurality of traffic routes over the switch, a signal at each end of each route for governing the movement of traffic in opposite directions over the route, a signal control relay for each signal having a manually controllable energizing circuit, a signal circuit for clearing each signal including front contacts of the associated signal control relay and back contacts of an opposing signal control relay selected in accordance with the position of the track switch, a locking relay associated with each signal circuit, means deenergizing each locking relay when the 60
- 75

- corresponding signal circuit is closed, and means controlled by each said locking relay when deenergized for preventing the operation of the opposing signal control relay.
- 5 10. In combination with a railway track switch, a plurality of traffic routes over the switch, a signal at each end of each route for governing the movement of traffic in opposite directions over the route, a signal control relay for each signal having a manually controllable energizing circuit, a signal circuit for clearing each signal including front contacts of the associated signal control relay and back contacts of an opposing signal control relay selected in accordance with the position of the track switch, a locking relay associated with each signal circuit, means deenergizing each locking relay when the corresponding signal circuit is closed, and means controlled by each said locking relay in accordance with the position of the track switch for preventing the operation of the opposing signal control relay as long as said locking relay is deenergized.
- 15 11. In combination with a stretch of railway track including a track switch, a signal at each end of the stretch for governing the movement of traffic over the stretch, a signal control relay and a locking relay for each signal, a control circuit for each signal including front contacts of the associated signal control relay and back contacts of the signal control relay for the opposing signal, said circuits having a portion in common including contacts controlled in accordance with the position of the track switch, a circuit for each locking relay closed only when the associated signal is at stop, and a circuit for each signal control relay including a manually controllable contact and a contact closed only when the locking relay for the opposing signal is energized.
- 20 12. In combination with a railway track layout comprising parallel tracks connected by crossover switches to form different traffic routes, a signal for each direction for each route, a signal control relay and a locking relay for each direction for each track; a route circuit for each signal, each route circuit including a front contact of the signal control relay at the entrance end of the route which such signal governs and indication contacts controlled by the switches of said crossover, each route circuit also including back contacts of the signal control relay at the exit end of said route; means for clearing each signal when its route circuit is closed and for then releasing the adjacent locking relay, and means controlled by each locking relay when released for preventing the operation of the crossover switches or of the signal control relay at the exit end of the closed route circuit.
- 25 13. In combination with a track layout including a plurality of track switches, a locking relay for each switch effective when deenergized to prevent operation of the switch, a signal for governing traffic movements over a particular route through said track layout, a route relay for controlling said signal, a manually controllable energizing circuit for said route relay including a front contact of each said locking relay, each such contact being bridged by a contact controlled by the corresponding switch and closed only when the switch position is in accordance with said route, and means controlled by said route relay when energized to operate each of the switches to a position to establish

- said route and to clear said signal when said route is established.
14. In combination, a traffic route including a plurality of railway track switches, a switch control relay for each switch of the route, a locking relay for each switch which when deenergized prevents the operation of its control relay, a route relay, a manually controllable pickup circuit for each route relay closed either when the track switches occupy positions to establish said route or their locking relays are energized, a stick circuit for said route relay, means controlled by said route relay when energized for operating the switch control relays to set up the route, a signal for governing the movement of traffic over the route, a circuit for clearing the signal closed only when said route relay is energized and each switch of the route agrees in position with its switch control relay, and means responsive to the clearing of said signal for releasing each of said locking relays.
- 15 15. In combination, a track layout including a plurality of track switches, a normal and a reverse manually operable control contact for each switch, a manually operable route relay, a normal control circuit for each switch including its normal manually operable control contact and in multiple therewith a front contact of said route relay, and a reverse control circuit for each switch including its reverse manually operable control contact and in series therewith a back contact of said route relay.
- 20 16. In a centralized traffic control system for railroads, a track layout including a plurality of track switches, a signal for each traffic route through said layout, code control means for each switch and signal for operating the switches to normal or reverse to establish different traffic routes and for clearing the signal for the established routes in response to different code signals, and other code controlled means for simultaneously operating a plurality of said switches in response to a single code signal to establish a particular traffic route through said layout and for clearing a signal governing traffic movements over said route when said route has been established by the operation of the track switches.
- 25 17. In a centralized traffic control system for railroads, a track layout comprising parallel tracks connected by crossover switches to form non-conflicting traffic routes when said switches are normal and a traffic route which includes both tracks when said switches are reversed, a signal for each route, a remote controlled relay for each end of each track for clearing the adjacent signal, an energizing circuit for each signal closed in response to the energization of the corresponding remote controlled relay when the route which such signal governs is established by the track switches, but only if the remote controlled relay for the opposing signal for the same route is deenergized, a locking relay for each end of each track which when deenergized prevents the operation of the track switches, means responsive to the clearing of a signal for releasing the adjacent locking relay, means controlled by that locking relay which is released when a signal for a route including both tracks is cleared for preventing the energization of the remote control relay which controls the opposing signal for the same route, and other means effective when such route is established for preventing the energization of the remote control relays which govern the signals for conflicting routes.
- 30 18. In combination, a track layout including a

- plurality of track switches, a route relay for each of a plurality of routes through said layout, means controlled by each route relay when energized to operate the track switches as required to establish the corresponding route, a switch locking relay for each switch energized only under conditions favorable for operation of the switch, and means preventing the energization of the route relay for any route when a locking relay for a switch of that route is deenergized and the position of said switch is not in accordance with the route.
19. In combination, a track layout including a plurality of track switches, a route relay for each of a plurality of routes through said layout, means controlled by each route relay when energized to operate the track switches as required to establish the corresponding route, a switch locking relay for each switch energized only under conditions favorable for operation of the switch, a manually operable contact for each route relay for controlling such relay, and means controlled jointly by each track switch of the corresponding route and by its switch locking relay for at times preventing the energization of such route relay in response to the operation of its manually operable contact.
20. In combination, a track layout including a plurality of track switches, a route relay for each of a plurality of routes through said layout, means controlled by each route relay when energized to operate the track switches as required to establish the corresponding route, a switch locking relay for each switch energized only under conditions favorable for operation of the switch, a manually operable contact for each route relay for at times energizing said route relay, and indication means associated with said contact and controlled jointly by each track switch of the corresponding route and by its switch locking relay for indicating when conditions are favorable for setting up said route by the energization of said route relay.
21. In combination, a track layout including a plurality of track switches, a route relay for a particular route through said layout, means controlled by said route relay when energized to operate the track switches as required to establish said route, a switch locking relay for each switch energized only under conditions favorable for the operation of the switch, a manually operable contact for at times energizing said relay, and indication means associated with said contact and controlled jointly by each track switch of the corresponding route and by its switch locking relay for indicating when conditions are favorable for setting up said route by the energization of said route relay.
- and controlled jointly by each track switch of the route and by its switch locking relay for indicating when conditions are favorable for setting up said route by the energization of said route relay.
22. In a centralized traffic control system for railroads, a track layout including one or more track switches adapted to form different traffic routes, signals for governing traffic movements in each direction over said routes, a locking relay for each signal which when deenergized prevents operation of any switch of the corresponding route, each such locking relay becoming deenergized when such signal is cleared, a signal control relay for each signal, an energizing circuit for each signal including in series, a front contact of the associated signal control relay, contacts controlled by one or more track switches in accordance with the route which such signal governs, a back contact of the opposing signal control relay, and a front contact of the locking relay for the opposing signal for the same route; and a circuit for each signal control relay including a manually controlled contact and a front contact of the locking relay for such opposing signal.
23. In a centralized traffic control system for railroads, a track layout including one or more track switches adapted to form different traffic routes, signals for governing traffic movements in each direction over said routes, a locking relay for each signal which when deenergized prevents operation of any switch of the corresponding route, each such locking relay becoming deenergized when such signal is cleared, a signal control relay for each signal, an energizing circuit for each signal including in series, a front contact of the associated signal control relay, contacts controlled by one or more track switches in accordance with the route which such signal governs, a back contact of the opposing signal control relay, and a front contact of the locking relay for the opposing signal for the same route; and a circuit for each signal control relay including a manually controlled contact and a front contact of the locking relay for such opposing signal.
